DES. 1947

John Rogers, of New York, N.Y.
Letters Patent No 1947-Dated May 17, 1864.
Design for a Statuette group of Figures.

The schedule referred to in these Letters Patent and making part of the same.

To all whom it may concern:

Be it known that I, John Rogers, of the City and County of New York, and State of New York, have invented or produced a new and original design for a group of figures; and I do hereby declare that the following is a full and exact description of the same. The group consists of three figures, and is called the Returned Volunteer. The central figure represents an old Blacksmith standing over his anvil - on his right, taking hold of his hand is a little girl. On his left is a soldier who has arranged some fortifications with the Blacksmith's tools, and is showing him how the fort was taken. All of which are clearly seen in the accompanying drawings; and what I claim as my invention or production, and desire to secure by Letters Patent, is - The design for a group of figures as shown and described.
